UNITED STATES PATENT OFFICE.

ERNEST S. ROE, OF PLYMOUTH, MICHIGAN.

AIR-PUMP GUN.

Application filed May 2, 1925. Serial No. 27,391.

To all whom it may concern:

Be it known that I, ERNEST S. ROE, a citizen of the United States, and resident of Plymouth, in the county of Wayne and State of Michigan, have invented new and useful Improvements in Air-Pump Guns, of which the following is a specification.

This invention relates to pump guns, and more particularly to that type of gun in which a power spring and compressed air are utilized for expelling the projectile.

Among the objects of my invention are the provision of simple and positively-acting leverage means for compressing the power spring; the arrangement of a safety latch under the control of the leverage means for preventing the actuation of the trigger until the leverage means has been completely returned to inoperative position, and the mounting of a magazine for projectiles within the barrel with provisions for automatically feeding one shot at a time in position to be discharged simultaneously with the operation of the spring compressing means.

Other objects and advantages will be apparent from the following description, wherein reference is made to the accompanying drawings illustrating a preferred embodiment of my invention and wherein similar reference numerals designate similar parts throughout the several views.

In the drawings:

Fig. 1 is a side elevation of the forward portion of my improved pump gun.

Fig. 2 is a central longitudinal section therethrough.

Fig. 3 is an enlarged detail view showing the leverage means for compressing the power spring; the parts being shown in inoperative position.

Fig. 4 is a similar view with the parts shown in the position assumed when the power spring is compressed.

Figs. 5 and 6 are detail cross sections taken substantially on the line 5—5 and 6—6 of Fig. 3.

Fig. 7 is a detail vertical section through the forward portion of the barrel; parts being broken away to show the interior construction of the projectile magazine.

Fig. 8 is a plan view of the projectile magazine and associated parts, the sur-

rounding barrel being shown in section.

Fig. 9 is a detail cross section taken substantially on the line 9—9 of Fig. 7. 55

Fig. 10 is a cross section taken substantially on the line 10—10 of Fig. 8.

Fig. 11 is a detail horizontal section taken substantially on the line 11—11 of Fig. 7 60 and showing the manner of securing the projectile magazine within the barrel.

Fig. 12 is an enlarged detail elevation of the central portion of the gun and showing the safety latch in engagement with the trigger guard so as to prevent the actuation of the trigger. 65

Fig. 13 is a detail cross section taken substantially on the line 13—13 of Fig. 12.

Fig. 14 is an enlarged detail view showing the contacting portions of the safety latch and trigger guard. 70

Fig. 15 is a detail perspective view of the trigger, and

Fig. 16 is a detail perspective view of the trigger guard. 75

Referring now to the drawings, the numeral 5 designates the stock of the gun, 6 the barrel and 7 an intermediate frame connected to both the stock and barrel. The 80 barrel 6 carries the usual front and rear sights 8 and 9 respectively, and houses the power spring 10, plunger 11, projectile magazine 12 and a smaller projectile barrel 13 positioned substantially centrally of the 85 main barrel 6 and adapted to receive a guide tube 14 projecting forwardly from the plunger 11. The guide tube 14 is hollow, as best shown in Fig. 7, and is apertured, as at 15, to permit the passage of air 90 through the interior to the tube to the projectile barrel 13 whenever the plunger 11 is forcibly impelled by the power spring 10. The guide tube 14 also is utilized to control the automatic feeding of successive projectiles from the magazine 12 into the projectile barrel 13 whenever the spring 10 is compressed by drawing the plunger 11 rearwardly, as will be hereinafter more fully described. 95

The plunger 11 is preferably constructed with a forward disc portion 11^a carrying a washer 11^b of leather or other suitable material and a stem 11^c extending through the power spring 10 and an abutment 16 secured within the gun barrel. The stem 11^c 100

is herein shown as formed of spaced side members of sheet steel or the like joined adjacent their rear extremities by a cross bar 11^a, which projects below the remainder of the side bars into position to be contacted by the sear 17 of the trigger 18 whenever the plunger stem is moved rearwardly to a sufficient extent. A cross pin 19 is also arranged through the side bars of the plunger stem slightly forwardly of the cross bar 11^a, and the extremities of the pin 19 extend into a pair of elongated guide slots 20 arranged in the sides of an inner frame 21, which, as best shown in Figs. 3 and 4, is mounted within the frame 7 between the abutment 16 and the trigger 18. The trigger 18 is pivoted within the frame 7 on the bolt 22 and is normally pressed forwardly by means of a light coil spring 23 positioned between a lug 24 on the trigger and the forward extremity of the stock 5. A channeled trigger guard 25 is also pivoted on the bolt 22 and straddles the projecting portion 18^a of the trigger, a finger, engaging portion 25^a being arranged forwardly of the projecting portion 18^a of the trigger so that the finger of the person shooting the gun will contact the trigger guard and not the trigger itself. As long as the trigger guard is free to move on the pivot bolt 22 the person shooting the gun need only to press rearwardly upon the trigger guard in the usual manner of shooting in order to release the compressed power spring 10 and so shoot a projectile then contained within the barrel 13, the rearward movement of the lower portion of the trigger guard 25 bringing the portion 25^a into engagement with the portion 18^a of the trigger and then further movement swinging the trigger simultaneously with the trigger guard to lower the sear 17 out of engagement with the cross bar 11^a of the plunger stem. Provisions are made, however, for interposing a safety latch 26 below the laterally projecting lugs 25^b of the trigger guard (note Fig. 16) whenever the spring compressing means is out of its normal inoperative position, as will be hereinafter more fully described.

The power spring compressing means comprises a hand block 27 slidably mounted upon a guide rod 28 below and parallel to the barrel 6, a lever 29 having a rolling fulcrum on the inner frame 21 and connected with the hand block 27 by the link 30, and a contact finger 31 pivoted on the lever 29 and engaging the forward portion of the cross pin 19 carried by the stem 11^c of the plunger 11. As best shown in Figs. 3 and 4, the lever 29 is formed with a plurality of teeth 29^a adjacent one extremity, which teeth mesh with a stationary rack 32 on the inner frame 21 to provide a constant positive engagement between the lever and the stationary frame regardless of the posi-

tion of the lever. The rack 32 may be formed integrally with the inner frame 21, as by punching suitable apertures in the frame to receive the teeth 29^a of the lever, cross bars being arranged intermediate the apertures so that their sides are engaged by the edges of the teeth during the swinging of the lever. To prevent the accidental dislocation of the teeth of the lever 29 from the rack 32, I preferably secure a guide pin 33 in the lever with its extremities extending into a pair of parallel guide slots 34 arranged in the inner frame 21 (note Figs. 3 and 4). The guide slots 34 are also utilized to prevent the falling of the contact finger 31, a guide pin 35 being secured within the finger 31 with its extremities extending into the guide slots 34. For rigidity and durability, I preferably form the lever 29 and link 30 of channeled sheet steel bent to the shape desired.

The operation of my improved power spring compressing means is believed to be apparent. Whenever the hand block 27 is slid rearwardly upon the guide rod 28 the lever 29 is rocked from the position shown in Fig. 3 to substantially the position shown in Fig. 4, the lever 29 rolling upon the stationary rack 32 and carrying the contact finger 31 and plunger 11 longitudinally rearward until the cross bar 11^a on the rear extremity of the plunger stem passes over the sear 17 of the trigger and enters the notch 18^b in the trigger. The trigger spring 23 permits the downward swinging movement of the sear 17 as the cross bar 11^a passes thereover, and then returns the sear to its original position, catching the cross bar 11^a and holding the plunger in substantially the position shown in Fig. 4. The hand block 27 is then slid forwardly to its normal position, returning the lever 29, link 30 and contact finger 31 to substantially the position shown in Fig. 3. This return movement of the contact finger in no way affects the position of the plunger stem, for the finger 31 is not secured to the plunger stem but merely engages the forward portion of the cross pin 19 carried by the plunger stem. Accordingly, the forward movement of the lever 29 moves the contact finger away from the cross pin 19.

During the swinging movement of the lever 29 to compress the power spring 10 the safety latch 26 is moved into position to prevent the downward swinging of the trigger guard 25 to thereby prevent the accidental pulling of the trigger 18 before the power spring compressing means has been returned to its normal position. As best shown in Figs. 2 and 12, the latch 26 is slidably mounted at one side of the inner frame 21 and is movably secured thereto by means of a screw 36 threaded into the frame 21 and passing through a slot 37 adjacent the forward ex-

tremity of the safety latch 26. Adjacent its rear extremity the latch 26 is provided with an inwardly and upwardly bent tab 26^a (note Fig. 13) which extends through 5 an elongated slot 38 in the frame 21. The rear portion of the slot 38 is directly beneath the normal position of the laterally extending lugs 25^b on the trigger guard 25, and whenever the latch 26 is moved to its 10 rearmost position the tab 26^a engages under one of the lugs 25^b of the trigger guard to prevent the swinging of the trigger guard into engagement with the trigger 18. Upwardly extending lugs 26^b and 26^c are provided adjacent the extremities of the safety latch 26 in position to be contacted by the guide pins 33 and 35 respectively during the swinging operation of the power spring compressing means. Thus, whenever the 15 hand block 27 is slid rearwardly to compress the power spring 10, the guide pin 35 carried by the contact finger 31 will engage the forward extremity of the rear lug 26^c and move the safety latch 26 rearwardly as far 20 as permitted by the slot 37, in so doing moving the tab 26^a into engagement with the underside of the lugs 25^b of the trigger guard. The safety latch remains in this 25 position, preventing the swinging of the trigger guard, until, during the return movement of the power spring compressing means, the guide pin 33 carried by the lever 29 contacts the rear extremity of the forward lug 26^b and moves the safety latch 26 30 forwardly as far as permitted by the slot 37, in so doing sliding the tab 26^a out of the path of movement of the lugs 25^b of the trigger guard. The forward lug 26^b is so 35 positioned relatively to the guide pin 33 that it will be engaged by the pin 33 only 40 when the spring compressing means has been almost completely returned to its normal inoperative position, and detachment of the tab 26^a from the lug 25^b of the trigger 45 occurs only when the power compressing means has reached its extreme forward position.

The mechanism for successively feeding projectiles to the inner barrel 13 will now 50 be described. An elongated container 12 houses a comparatively light spring 38 (note Fig. 7) abutting at its forward extremity upon the screw 39 or other means 55 for closing the forward extremity of the container 12 and at its rear extremity against a traveler 40 adapted to move longitudinally of the container under the impulse of the spring 38. The rear extremity of the container is provided with an 60 aperture 41 arranged to align with an aperture 42 in the upper portion of the inner barrel 13, an inclined lug 43 being arranged above the aperture 41 to guide shot 44 or 65 other projectiles through the aligned apertures into the barrel 13. In loading, the

container 12 is removed from its normal position within the outer barrel 6 and a plurality of projectiles 44 inserted through the aperture 41 into the container, the spring 38 being compressed and the traveler 40 70 moved toward the forward extremity of the container as the projectiles are introduced. When a sufficient number of projectiles have been inserted within the container 12, it is returned to the position shown 75 in Fig. 7, a spring latch 45 being provided to retain the magazine in position as long as desired. As best shown in Fig. 11 the latch 45 is secured at its rear extremity to the container 12 and is provided with a burr 46 adapted to contact the rear face of the end closure 47 of the barrel 6. The forward extremity of the latch 45 is bent, substantially as shown at 48, to provide a finger contact whereby the burr 46 80 may be readily swung out of engagement with the closure 47 to permit the withdrawal of the magazine whenever it is desired to reload.

In operation, whenever the tube 14 carried by the plunger 11 is moved rearwardly to substantially the position shown in Fig. 7, the rearmost projectile 44 will fall through the aligned apertures 41 and 42 90 into position to be discharged upon release of the power spring 10 from its compressed position, as whenever the trigger is pulled to shoot the gun. The forward movement of the plunger 11 under the impulse of the spring 10 will carry the tube 14 within the barrel 13 and so block the apertures 41 and 42 to prevent the further falling of projectiles into the barrel. Accordingly, no more projectiles will fall until the plunger 11 is again moved rearwardly during the 95 compressing of the power spring 10. When the plunger has again reached its rearmost position the tube 14 will clear the aperture 42 and permit another projectile to fall into position within the barrel 13.

To facilitate the loading of the magazine 12, I preferably provide a wing 40^a upon the traveler 40 and a longitudinal slot 12^a in which the wing 40^a is guided (note Figs. 9 and 10). The rear extremity of the traveler 40 may also be tapered, substantially as shown in Fig. 7, to tend to roll the projectiles along the container as successive projectiles are deposited within the barrel 13.

While it will be apparent that the illustrated embodiment of my invention herein disclosed is well calculated to adequately fulfill the objects and advantages primarily stated, it is to be understood that the invention is susceptible to variation, modification and change within the spirit and scope of the subjoined claims.

Having described my invention, I claim 130

1. In a gun, the combination of a sta-

tionary frame, a power spring, a plunger engaging one extremity of the spring, and means for compressing the spring including a lever having a rolling fulcrum on the frame, a member carried by the lever and engaging the plunger stem, and means for rocking the lever.

2. In a gun, the combination of a stationary frame, a power spring, a plunger 10 engaging one extremity of the spring, and means for compressing the spring including a lever having a rolling fulcrum on the frame, a member carried by the lever and engaging the plunger stem, and means for 15 rocking the lever including a slidable hand block and a link pivoted to the hand block and lever.

3. In a gun, the combination of a stationary frame, a power spring, a plunger 20 engaging one extremity of the spring, and means for compressing the spring including a lever having a rolling fulcrum on the frame, a member carried by the lever and engaging the plunger stem, means for rocking 25 the lever, and a trigger arranged to catch the plunger stem when the spring is compressed.

4. In a gun, the combination of a stationary frame, a power spring, a plunger 30 engaging one extremity of the spring, and means for compressing the spring including a lever having a rolling fulcrum on the frame, a member carried by the lever and engaging the plunger stem, means for 35 rocking the lever, and means for maintaining the lever in contact with the frame during its rocking movement including a guide 40 slot secured in the lever, there being a guide slot arranged in the frame and receiving one extremity of the guide pin.

5. In a gun, the combination of a stationary frame, a power spring, a plunger engaging one extremity of the spring, and means for compressing the spring including 45 a lever having a rolling fulcrum on the frame, a member carried by the lever and engaging the plunger stem, means for rocking the lever, and means for preventing the accidental dislocation of the lever and said 50 member from the frame including guide pins secured in the lever and member respectively, there being a guide slot arranged in the frame and receiving one extremity of said guide pins.

6. In a gun, the combination of a stationary frame, a power spring, a plunger engaging one extremity of the spring, and means for compressing the spring including 55 a lever having a rolling fulcrum on the frame, a member carried by the lever and engaging the plunger stem, means for rocking the lever, and means for preventing the accidental dislocation of the lever and said member from the frame including guide 60 pins secured in the lever and member re-

spectively, there being a pair of aligned guide slots arranged in the frame and receiving the extremities of said guide pins.

7. In a gun, the combination of a stationary frame, a power spring, a plunger 70 engaging one extremity of the spring, and means for compressing the spring including a lever having a rolling fulcrum on the frame, a member carried by the lever and engaging the plunger stem, means for rocking 75 the lever, a trigger arranged to catch the plunger stem when the spring is compressed, a trigger guard mounted adjacent the trigger, and means under the control of the spring compressing means for preventing the movement of the trigger guard until the spring compressing means has been returned to its normal inoperative position.

8. In a gun, the combination of a stationary frame, a power spring, a plunger 80 engaging one extremity of the spring, and means for compressing the spring including a lever having a rolling fulcrum on the frame, a member carried by the lever and engaging the plunger stem, means for rocking 85 the lever, a trigger arranged to catch the plunger stem when the spring is compressed, and means under the control of the spring compressing means for preventing the release of the trigger from the plunger stem until the spring compressing means has been returned to normal inoperative 90 position.

9. In a gun, the combination of a stationary frame, a power spring, a plunger 95 engaging one extremity of the spring, and means for compressing the spring including a lever having a rolling fulcrum on the frame, a member carried by the lever and engaging the plunger stem, means for rocking 100 the lever, a trigger arranged to catch the plunger stem when the spring is compressed, and means under the control of the spring compressing means for preventing the release of the trigger from the plunger stem until the spring compressing means has been returned to normal inoperative 105 position including a slidable latch mounted on the frame and adapted to be contacted by the spring compressing means whenever the 110 lever is rocked in either direction.

10. In a gun, the combination of a stationary frame, a power spring, a plunger 115 engaging one extremity of the spring, and means for compressing the spring including a lever having a rolling fulcrum on the frame, a member carried by the lever and engaging the plunger stem, means for rocking 120 the lever, a trigger arranged to catch the plunger stem when the spring is compressed, and means under the control of the spring compressing means for preventing the release of the trigger from the plunger 125 stem until the spring compressing means has been returned to normal inoperative 130 position.

- position including a slidable latch mounted on the frame and having a pair of lugs arranged so that one of said lugs is contacted by the spring compressing means whenever the lever is rocked in either direction.
11. In a gun, the combination of a stationary frame, a power spring, a plunger engaging one extremity of the spring, and means for compressing the spring including a lever having a rolling fulcrum on the frame, a member carried by the lever and engaging the plunger stem, means for rocking the lever, a trigger arranged to catch the plunger stem when the spring is compressed, a trigger guard pivoted adjacent the trigger and having a laterally extending lug, and means under the control of the spring compressing means for engaging said lug to prevent the movement of the trigger guard until the spring compressing means has been returned to normal inoperative position.
12. In a gun, the combination of a stationary frame, a power spring, a plunger engaging one extremity of the spring, and means for compressing the spring including a lever having a rolling fulcrum on the frame, a member carried by the lever and engaging the plunger stem, means for rocking the lever, a trigger arranged to catch the plunger stem when the spring is compressed, a trigger guard pivoted adjacent the trigger and having a laterally extending lug, and means under the control of the spring compressing means for engaging said lug to prevent the movement of the trigger guard until the spring compressing means has been returned to normal inoperative position, including a movable latch mounted upon the frame and adapted to be contacted by the spring compressing means while the spring is being compressed to move the latch into the path of movement of said lug.
13. In a gun, the combination of a stationary frame, a power spring, a plunger engaging one extremity of the spring, and means for compressing the spring including a lever having a rolling fulcrum on the frame, a member carried by the lever and engaging the plunger stem, means for rocking the lever, a trigger arranged to catch the plunger stem when the spring is compressed, a trigger guard pivoted adjacent the trigger and having a laterally extending lug, and means under the control of the spring compressing means for engaging said lug to prevent the movement of the trigger guard until the spring compressing means has been returned to normal inoperative position including a slidable latch mounted upon the frame and adapted to be moved by the spring compressing means into and out of the path of movement of said lug.
14. In a gun, the combination of a stationary frame, a power spring, a plunger engaging one extremity of the spring, and means for compressing the spring including a lever having a rolling fulcrum on the frame, a member carried by the lever and engaging the plunger stem, means for rocking the lever, a trigger arranged to catch the plunger stem when the spring is compressed, a trigger guard pivoted adjacent the trigger and having a laterally extending lug, and means under the control of the spring compressing means for engaging said lug to prevent the movement of the trigger guard until the spring compressing means has been returned to normal inoperative position including a slidable latch mounted upon the frame and having a tab adapted to be moved by the spring compressing means into and out of the path of movement of said lug.
15. In a gun, the combination of a stationary frame, a power spring, a plunger engaging one extremity of the spring, and means for compressing the spring including a fixed rack carried by the frame, a lever having a toothed portion engaging the rack, a member carried by the lever and contacting the plunger stem, and means for rocking the lever.
16. In a gun, the combination of a stationary frame, a power spring, a plunger engaging one extremity of the spring, and means for compressing the spring including a fixed rack carried by the frame, a lever having a toothed portion engaging the rack, a member carried by the lever and contacting the plunger stem, means for rocking the lever, and means for maintaining the lever teeth in engagement with the rack including a guide pin fixed upon the lever, there being a guide slot arranged in the frame and receiving one extremity of the guide pin.
17. In a gun, the combination of a stationary frame, a power spring, a plunger engaging one extremity of the spring, and means for compressing the spring including a fixed rack carried by the frame, a lever having a toothed portion engaging the rack, a member carried by the lever and contacting the plunger stem, means for rocking the lever, and means for preventing the accidental dislocation of the lever and contact member including guide pins carried by the lever and member respectively, there being a guide slot arranged in the frame and receiving one extremity of each guide pin.
18. In a gun, the combination of a stationary frame, a power spring, a plunger engaging one extremity of the spring, and means for compressing the spring including a fixed rack carried by the frame, a lever having a toothed portion engaging the rack, a member carried by the lever and contacting the plunger stem, means for rocking the lever, and means for preventing the acci-

dental dislocation of the lever and contact member including guide pins carried by the lever and member respectively, there being a pair of aligned slots arranged in the frame 5 and receiving the extremities of said guide pins.

19. In a gun, the combination of a stationary frame, a power spring, a plunger engaging one extremity of the spring, and 10 means for compressing the spring includ-

ing a fixed rack carried by the frame, a lever having a toothed portion engaging the rack, a member carried by the lever and contacting the plunger stem, and means for rocking the lever including a slideable hand block 15 and a link connecting the hand block and lever.

In witness whereof I hereunto set my hand.

ERNEST S. ROE.
